FIRE ALARM TAPE

Waldo H. Kliever and Lincoln G. Ekman, Minneapolis, Minn., assignors to Minneapolis-Honeywell Regulator Company, Minneapolis, Minn., a corporation of Delaware

Application May 29, 1950, Serial No. 165,052

6 Claims. (Cl. 200—143)

1

This invention is concerned with the sensing element for a fire alarm system and more particularly with the fusible wire type of sensing element adapted to extend about a room which is to be protected as to fire or a dangerously high temperature condition. It is therefore an object of this invention to provide a new and improved type of fire alarm sensing element.

Another object of the invention is to provide a tape enclosing a fusible wire for sensing fire or dangerously high temperature conditions.

Another object of the invention is to provide a fire alarm tape enclosing a fusible wire that can be easily attached to the walls of a room.

Another object of the invention is to provide a fire alarm tape in which the fusible wire is so positioned within the tape as to insure a break in the wire upon melting.

Another object of the invention is to provide a new and improved fire alarm apparatus utilizing a fire alarm tape.

Briefly, the invention encompasses a tape having a first strip of material, such as paper, with the fusible wire carried by the paper strip and describing an undulating path along the strip. A second paper strip, which may be so colored as to harmonize with the color scheme of the room, is placed on the first strip over the wire to conceal the wire. A longitudinally divided strip, perhaps of plastic, may be placed between the two paper strips above and below the wire. The division of the strip may be such as to describe a sine wave, or saw teeth or a combination of both to insure that the wire, upon melting, breaks to open the circuit containing the wire. The plastic strip also serves the purpose of causing the outer surface of the tape to be completely flat and present a good appearance.

For a better understanding of the invention reference is had to the following detailed description taken in conjunction with the accompanying drawings, in which:

Figure 1 shows a fire alarm apparatus utilizing one form of the tape, shown partly in section;

Figure 2 is a modification, partly in section, of the tape shown in Figure 1;

Figure 3 is another modification, partly in section of the tape; and

Figure 4 is a cross-sectional view of the tape of Figure 1 taken along the line 4—4.

In the apparatus shown in Figure 1 a tape 10 is shown to have a base strip 11 of paper or other suitable insulating material. A strip of a suitable plastic, may be divided longitudinally into two strips 12 and 13 and attached to the strip

2

11 so as to have a gap 14 between the two strips 12 and 13. A fusible wire 15 of Woods metal or some other suitable metal having a melting point at a low temperature, is placed in the gap 14 between the two plastic strips 12 and 13. A strip 16, of paper or some other suitable insulating material, is placed over the two plastic strips and the wire and conceals them. The wire has a diameter less than the width of the gap 14 and is also less than the thickness of the strips 12 and 13 to permit the metal, upon the wire melting, to flow freely into the depressions along the upper edge of strip 13 and insure a break in the wire. Because the thickness of the strips 12 and 13 are greater than the diameter of the wire 15 it would be possible for the wire to lie along the upper edge of strip 13 and still insure a break because the extra width of the strips would provide a space into which the melted metal could flow from the rises into the depressions. As shown in the drawing, the upper edges of the strips 11 and 16 and the upper edge of the plastic strip 12 are all adjacent each other as are the lower edges of strips 11 and 16 and plastic strip 13. The plastic strips 12 and 13 may be cut from a single strip by dividing the strip longitudinally so that the division, as shown in Figure 1, describes a sine wave.

The wire 15 should be placed in the gap between the two plastic strips under sufficient tension so that the wire does not lie completely along the upper edge of plastic strip 13. Upon melting due to a fire or any other temperature rise which would indicate a dangerous condition, the wire will tend to pull apart due to its own weight and flow into the space provided by the valleys in the lower strip 13.

The outer surface of the strip 11 may be adhesive in order that the tape may be easily fastened to a wall about a room. The plastic strips may be fastened to the strip 11 either by providing an adhesive surface to the plastic strips or to the inner surface of the strip 11. The inner surface of strip 16 may be made adhesive in order to be easily joined to the plastic strips. The outer surface of strip 16 may be decorated in various fashions or be a plain color in order to harmonize with the color scheme in the room in which the tape is placed. The tape may be used as a borderline around the room such as to cover or form the upper edge of wallpaper in the room.

The ends of the fusible wire 15 are connected to conducting wires 17 and 20 and to a battery 21. A relay 22 has an energizing coil 23 con-

nected in series with the fusible wire 15 and the conductors 17 and 20 and the battery 21. Thus it can be seen that as long as the wire 15 is not subjected to undue temperature the circuit through the energizing coil 23 is complete and the coil is energized.

Relay 22 has a pair of contacts 24 and 25 which, as shown in Figure 1, are open when the relay winding is energized, which is the normal condition of the circuit. An alarm 26, of any suitable type, is placed in series with the contacts 24 and 25 across a source of power, here shown as being the battery 21. If desired, of course, a separate energizing source for the alarm circuit could be used.

As can be seen, the alarm 26 is unenergized as long as the circuit is in its normal operating condition and the wire 15 has no breaks in it. Upon a temperature rise sufficient to melt the fusible wire 15, this wire will break and open the energizing circuit to coil 23, permitting relay contacts 24 and 25 to close. This completes the energizing circuit to the alarm 26 and the alarm is energized.

It is apparent that a failsafe apparatus has been provided in that should the fusible wire 15 or the conductors 17 or 20 break for any reason at all the relay coil 23 will be deenergized to complete the energizing circuit to the alarm.

The tape shown in Figure 2 is very similar to the tape of Figure 1 and shows the base strip 11 with the two plastic strips 12 and 13a placed on the strip 11. The fusible wire 15 is also similar to the fusible wire shown in Figure 1 and the covering strip 16 is also the same. The only difference between the tape of Figure 2 and the tape shown in Figure 1 is that the upper edge of the plastic strip 13a in Figure 2 has saw teeth 27 along its sine wave edge to further insure a break in the fusible wire 15 upon the wire melting in that the saw teeth in the upper edge of the plastic strip 13 provides additional rises and depressions for the metal to flow into. A break in the wire is further insured in that the sharp edges tend to sever the wire when it is softened by heat.

The tape shown in Figure 3 is similar to the tapes shown in Figures 1 and 2 as to the bottom strip 11 and the top strip 16 with the only difference being in the manner of making the longitudinal division in the plastic strip positioned between the two paper strips. In the plastic strip shown in Figure 3 the division between the two plastic strips 12b and 13b forms a saw-toothed gap rather than a sine wave gap, as is shown in Figure 1. The fusible wire 15 in the tape of Figure 3 is the same as the fusible wire in the tapes of Figures 1 and 2.

The cross-sectional view of the tape of Figure 4 shows the paper strip 11 with the plastic strips 12 and 13 on the paper strip 11 with the fusible wire 15 in the gap between the two plastic strips. The paper strip 16 covers the two plastic strips, the fusible wire and the gap between the two plastic strips. As can be seen in Figure 4, the plastic strips 12 and 13 are of greater thickness than the diameter of fusible wire 15 in order that the wire will not be laterally supported by the base and top strips 11 and 16 with a secondary consideration of neatness in that the wire 15 will not rise above the plastic strips and thus cause a ridge along the entire tape due to the unevenness of strip 16 in bulging over the fusible wire. Also, the gap between the plastic strips 12 and 13 is greater than the diameter of wire 15 in order to provide ample space for the metal of the wire

to flow when the wire melts due to a rise in temperature. The cross sectional views of Figures 2 and 3 would be very similar to the cross sectional view of Figure 1 and therefore cross sectional lines have been shown in Figures 2 and 3.

This tape is easy to manufacture, is inexpensive, may be very easily applied to the walls of a room, and may decoratively harmonize with the color scheme of the rest of the room to provide a simple, reliable means of protecting against fires in any type of room.

Obviously, modifications of this idea may be easily made by those skilled in the art without departing from the spirit of this invention which is to be defined and limited only to the extent of the appended claims.

We claim as our invention:

1. A tape for use in a fire alarm system, comprising: a first flat strip of flexible insulating material; a second strip of flexible insulating material on said first strip; a fusible wire of small cross-section on said first strip and above said second strip; and a third flat strip of flexible insulating material on said first strip such as to enclose said second strip and said wire between said first and third strips, the thickness of said second strip being greater than the diameter of the wire, providing a space for the wire, upon melting, to flow and break the wire.

2. A tape for use in a fire alarm system, comprising: a first flat strip of flexible insulating material; a second strip of flexible insulating material on said first strip, said second strip having an upper edge shaped to form rises and depressions; a fusible wire of small cross-section on said first strip and above the upper edge of said second strip; and a third flat strip of flexible insulating material on said first strip so as to enclose said second strip and said wire between said first and third strips, the thickness of said second strip being greater than the diameter of the wire, providing a space above the rises and depressions along the upper edge of the second strip so that the wire, upon melting, flows from the rises into the depressions and breaks the wire.

3. A tape for use in a fire alarm system, comprising: a first flat strip of insulating material having an upper and a lower edge; a second strip of flexible insulating material, having an upper and a lower edge, on said first strip such that the lower edge of the second strip is adjacent the lower edge of the first strip, the upper edge of the second strip having rises and depressions therein; a third strip of flexible insulating material, having an upper and a lower edge, on said first strip such that the upper edge of the third strip is adjacent the upper edge of the first strip, said second and third strips having such dimensions that there is a gap between said second and third strips; a fusible wire of small cross-section in the gap between said second and third strips, said gap being larger than said wire, providing a space about said wire; and a fourth flat strip of flexible insulating material, having an upper and a lower edge, on said first strip such as to enclose the second and third strips and the wire between the first and fourth strips, the upper and lower edges of said fourth strip being adjacent the upper and lower edges respectively of said first strip, the rises and depressions of the upper edge of the second strip causing the wire, upon melting, to flow from the rises into the depressions and break the wire, one of said strips hav-

ing an adhesive surface for attaching the tape to a wall.

4. A tape for use in a fire alarm system, comprising: a first flat strip of insulating material having an upper and a lower edge; a second strip of flexible insulating material, having an upper and a lower edge, on said first strip such that the lower edge of the second strip is adjacent the lower edge of the first strip, the upper edge of the second strip being shaped to form a sine wave; a third strip of flexible insulating material, having an upper and a lower edge, on said first strip such that the upper edge of the third strip is adjacent the upper edge of the first strip, said second and third strips having such dimensions as to form a gap between said strips; a fusible wire of small cross-section in the gap between said second and third strips, said gap being larger than said wire, providing a space about said wire; and a fourth flat strip of flexible insulating material, having an upper and a lower edge, on said first strip such as to enclose the second and third strips and wire between the first and fourth strips, the upper and lower edges of said fourth strip being adjacent the upper and lower edges respectively of said first strip, the sine wave upper edge of the second strip causing the wire, upon melting, to separate and thus break the wire.

5. A tape for use in a fire alarm system, comprising: a first flat strip of insulating material having an upper and a lower edge; a second strip of flexible insulating material, having an upper and a lower edge, on said first strip such that the lower edge of the second strip is adjacent the lower edge of the first strip, the upper edge of the second strip being shaped to form a sine wave having saw teeth along the edge; a third strip of flexible insulating material, having an upper and a lower edge, on said first strip such that the upper edge of the third strip is adjacent the upper edge of the first strip, said second and third strips having such dimensions as to form a gap between said strips; a fusible wire of small cross-section in the gap between said second and third strips, said gap being larger than said wire, providing a space about said wire; and a fourth flat strip of flexible insulating material, having an upper and a lower edge,

on said first strip such as to enclose the second and third strips and wire between the first and fourth strips, the upper and lower edges of said fourth strip being adjacent the upper and lower edges respectively of said first strip, the saw-toothed sine wave upper edge of the second strip causing the wire, upon melting, to separate and thus break the wire.

10 6. A tape for use in a fire alarm system, comprising: a first flat strip of insulating material having an upper and a lower edge; a second strip of flexible insulating material, having an upper and a lower edge, on said first strip such that the lower edge of the second strip is adjacent the lower edge of the first strip, the upper edge of the second strip being shaped to form saw teeth; a third strip of flexible insulating material, having an upper and a lower edge, on said first strip such that the upper edge of the third strip is adjacent the upper edge of the first strip, said second and third strips having such dimensions as to form a gap between said strips; a fusible wire of small cross-section in the gap between said second and third strips, said gap being larger than said wire, providing a space about said wire; and a fourth flat strip of flexible insulating material, having an upper and a lower edge, on said first strip such as to enclose the second and third strips and wire between the first and fourth strips, the upper and lower edges of said fourth strip being adjacent the upper and lower edges respectively of said first strip, the saw-toothed upper edge of the second strip causing the wire, upon melting, to separate and thus break the wire.
